BANANA TRAY

Richard F. Reifers, New Canaan, Thomas B. Kennedy
and William J. Hrozencik, Stamford, Conn., assignors
to Diamond National Corporation, New York, N.Y., a
corporation of Delaware

Filed Dec. 18, 1962, Ser. No. 72,896

Term of patent 14 years

(Cl. D58—12)

FIG. 1

FIG. 2

FIG. 3

FIG. 4.

FIG. 5.

FIG. 6.

FIG. 7.

FIGURE 1 is a top plan view of a banana tray embodying our new design;

FIGURE 2 is a bottom plan view of the banana tray illustrated in FIG. 1;

FIGURE 3 is an end elevational view looking from right to left at the banana tray of FIG. 1;

FIGURE 4 is an elevational view looking from right to left at FIG. 3; and

FIGURES 5-7 are sectional views with portions shown in elevation taken along lines 5-5, 6-6 and 7-7 of FIG. 1, respectively, and looking in the direction of the arrows.

We claim:

The ornamental design for a banana tray, as shown.
